CIRCUIT INTERRUPTER

James M. Wallace, North Braddock, Pa., assignor
to Westinghouse Electric Corporation, East
Pittsburgh, Pa., a corporation of Pennsylvania

Application July 12, 1940, Serial No. 345,051

21 Claims. (Cl. 200—89)

1

My invention relates to circuit interrupters, in general, and more particularly to circuit breakers of the automatic reclosing type.

One object of my invention is to provide a circuit breaker with novel means for automatically opening and then reclosing its contacts a predetermined time after the opening operation.

My invention is particularly directed to so-called small oil circuit breakers of the type where the circuit is interrupted in an arc extinguishing liquid such as oil, and where the operating mechanism is relatively simple and compactly arranged so that the whole device may be arranged, preferably, in an insulating casing having a pair of terminals, for easy and convenient mounting on a pole or other support for transmission and distribution lines.

The circuit breaker of my invention is especially adapted for the replacement of fuses used for the protection and maintenance of service on transmission lines. Such a circuit breaker may be mounted on the same support required for fuses, and has the advantage over simple fuse installations of being able to quickly restore service on the protected line following self-clearing faults. This type of circuit breaker has the further advantage over all types of fuse structures including repeating fuse structures, of not requiring the replacement of any parts following an interrupting operation. In fact, the circuit breaker of my invention will require substantially no attention until a permanent fault appears on the circuit protected, and after such a fault has been cleared, only a simple manual manipulation is required to restore the breaker to operative condition.

Although I have designed my invention for a specific use and embodied same in a particular type of apparatus wherein it has certain particular novel features of combination and utility, it will be obvious to persons skilled in the art that certain features of the invention will be useful in connection with other types of circuit breakers or interrupters.

Another object of my invention is to provide in an automatic reclosing type of circuit interrupter, novel tripping means designed to provide different tripping characteristics for successive circuit opening operations of the interrupter.

It is desirable for coordination with transformers, fuse links and other circuit breakers, that the first tripping of an automatic reclosing circuit breaker be a time delayed trip, especially on light overloads, inasmuch as such overloads cannot harm a circuit provided they are not continued

too long. However, if the fault is permanent, the succeeding trips should be substantially instantaneous to prevent damage to the circuit, and operation of other protective devices.

Another object of my invention is to provide in a circuit breaker, novel means operative in response to overloads for first slightly separating the breaker contacts, and for thereafter utilizing pressure developed by the arc formed for further separating said contacts.

Another object of my invention is to provide novel tripping means for a circuit breaker operable in response to overload currents for separating the breaker contacts.

Another object of my invention is to provide a novel type of interruption chamber for a circuit breaker which is especially adapted to utilize pressures generated by the arc to aid in separating the breaker contacts.

A further object of my invention is to provide novel circuit breaker operating mechanism, which is operable to close the breaker contacts automatically a predetermined time following a circuit interrupting operation.

Another object of my invention is to provide in an automatically reclosing type of circuit breaker, novel means for predetermining the number of successive reclosures, after which the breaker contacts are maintained in an open circuit position.

A still further object of my invention is to provide an automatic reclosing type of circuit breaker with novel means for maintaining the breaker contacts separated in response to a predetermined number of successive reclosures thereof, but which is ineffective to maintain said contacts separated in response to any number of nonsuccessive reclosures.

Another object of my invention is to provide a circuit breaker having contacts separable in an arc chamber, with novel means for flushing said chamber after each interrupting operation.

Another object of my invention is to provide a circuit breaker of the type described having a novel construction and arrangement of parts such as to provide a smaller, lighter, and more economical breaker than has heretofore been deemed practical.

These and other objects of my invention will become more apparent upon consideration of the following specification of preferred embodiments thereof, taken in connection with the attached drawings, in which:

Figure 1 is a substantially central longitudinal

sectional view through a circuit interrupter constructed in accordance with my invention;

Fig. 2 is a partial sectional view of the upper end of the interrupter shown in Fig. 1, and illustrating certain parts of the operating mechanism in elevation and in a position corresponding to an open position of the interrupter;

Fig. 3 is a side elevational view partly in section of the operating mechanism shown in Fig. 2 and taken substantially along the line III—III of Fig. 2;

Fig. 4 is a cross-sectional view through the arc chamber shown in Fig. 1, and substantially on the line IV—IV of Fig. 1;

Fig. 5 is a partial cross-sectional view of the upper end of an interrupter similar to that shown in Fig. 1 but illustrating a modified form of tripping mechanism; and

Fig. 6 is a partial central cross-sectional view of the interrupter shown in Fig. 5 taken substantially at right angles to the plane of Fig. 5.

In general, my invention is embodied in a circuit interrupter having a pair of separable contacts which are initially separated a distance sufficient to draw an arc between the contacts in an arc chamber, which chamber is designed to be filled with an arc-extinguishing medium such as oil or the like, and the contacts are arranged so that the pressure generated by the arc and due to the decomposition of the oil operates to further separate the contacts against the bias of a spring which normally maintains the contacts closed. As soon as the arc is extinguished, the spring is then free to reclose the contacts, but its action is retarded by a time delay means operable only when the contacts are closing. This time delay means is related to the contact closing means in such a manner as to permit a predetermined number of successive reclosures. For example, upon the occurrence of a permanent fault on the line the time delay means will act to lock or maintain the contacts in an open position following a predetermined number of reclosures thereof.

I will disclose herein two species of current responsive means for initially separating the contacts to establish an arc therebetween. In one embodiment of my invention the contact which is normally stationary is mounted for limited movement to and from the movable contact under the influence of a solenoid connected in the circuit. In another form of my invention, the movable contact is mechanically moved by a spring or other biasing means a short distance in response to operation of current responsive latch means for the biasing means. My invention further contemplates the use of a pair of latch means for the mechanical contact tripping means, with each latching means being operable in response to predetermined current conditions in a circuit and having different time characteristics. These latch means are so arranged that successive interrupting operations of the circuit breaker without appreciable time between successive interruptions, for example, as on the occurrence of a permanent fault in the circuit, will occur with different time characteristics.

Referring to Figures 1 to 4 of the drawings, I have illustrated one form of my novel circuit breaker as being contained in an insulating tubular casing 2, which may be of any desired insulating material, such as porcelain, glass, or the like. The casing 2, as shown in Fig. 1, has a closed bottom end portion and an open top. The open top is provided with an upper terminal

cover assembly 4, and the closed bottom of the casing is provided with a lower terminal assembly 6. An intermediate portion on the casing has a substantially cylindrical wall portion 8 upon which is mounted a cushioning sleeve 10 of rubber, fiber or the like, and on opposite sides of which may be clamped supporting brackets 12 (only one of which is shown), as by bolts 14. The outer end of bracket 12 may be turned laterally at 17 and apertured as at 18 for the reception of a bolt for securing the brackets in position on a pole or other supporting structure.

The lower terminal assembly 6 is mounted at the closed bottom portion of the insulating casing 2 by means of a bolt 18 extending through an aperture 19 in the closed end of the casing 2, and the bolt is provided with an enlarged disc-like head portion 20 positioned within the casing 2, with packing material 22 interposed between the head 20 and the adjacent inner surface of the closed end of the insulating casing 2. The packing material 22 may be of any desired packing material, preferably one resistant to oil, such for example, as cork, fiber or synthetic rubber. Bolt 18 has a bore 18 therethrough, the outer end of which is closed by a threaded plug 21, for the purpose of draining casing 2 when desired. The bolt 18 is secured in position by a nut 24 drawn up on the bolt against a washer 26 positioned between the nut 24 and the outer wall of the closed end of the casing 2. A terminal strap 28 may be also secured to the bolt 18 as by means of a second nut 30, as shown.

The upper terminal assembly 4 is in the form of a cover for the open end of the casing 2, which not only acts as a cap or cover for the casing, but, as will be hereinafter more fully explained, acts as a support for the interrupter and its operating mechanism when in operative position within the casing 2. Referring to Figs. 1 and 6, it will be noted that the cover 32 is provided with a transversely extending relatively hollow portion for the reception of certain parts of the circuit breaker operating mechanism, and the top wall of which is provided with an aperture for the reception of a screw threaded filler plug 34, so that the supply of arc-extinguishing fluid within the casing 2 may be renewed when necessary. The cover 32 includes a peripheral flange portion 36 adapted to seat on the upper end walls of casing 2, and this flange has at its outer edge a downwardly turned lip portion 38, for properly positioning the cover on the open end of the casing 2. Packing material 40 is interposed between the cover and the open end of the casing similar to the packing material 22, and the cover 32 is secured to the casing 2 by means of a support 42 fixedly mounted on the outside of the casing 2. The support 42 is in the form of an annulus which is substantially channel-shaped in cross-section, with the channel facing the outer surface of casing 2. The annular support 42 is secured to the casing by cast metal or the like 44, which is poured in between the support 42 and the outer casing wall so as to enter within the channel of the support 42 and between corrugations 46 provided on the outer surface of the casing to securely anchor the support 42 thereto. I provide a plurality (only one of which is shown) of laterally extending ears 50 and 52 on the support 42 and cover flange 36, respectively, which ears are apertured for the reception of bolts 48 for securing the cover to the supporting flange 42 and, therefore, to the insulating casing 2.

The insulating casing 2 may be of any desired shape and cross-section, preferably circular as shown, so that the hollow portion of the cover 32 described above extends substantially diametrically of the casing and so that segmental portions of cover flange 36 extend inwardly over the open end of the casing as shown at 54 in Fig. 6. Secured to these segmental portions of the cover flange 36 are spaced supporting plates 56 having angularly bent ends insulatingly secured to the segments 54 of the cover flange 36, by machine screws 57, with interposed insulating washers 58, and insulating bushings 60. The insulating washers 58 and bushings 60 may be of any desired insulating material such as fiber, or a synthetic resin material. As shown, the supporting plates 56 extend substantially parallelly downwardly in the tubular insulating casing 2, and one function of these plates is to support a substantially closed arc chamber 62, the upper end of which is secured between the lower ends of the supporting plates 56 in any desired manner, such, for example, as by welding or the like.

The arc chamber 62 includes an insulating tubular portion 64 which may be of any desired insulating material preferably fiber or a synthetic resin, which tube is threaded at each end thereof for the reception of upper and lower end caps 66 and 68, respectively. The upper end cap 66 is provided with an integral offset portion provided with a substantially cylindrical open topped cavity therein to form a dashpot cylinder 70 which will be hereinafter further described. The upper end cap 66 is also provided with an aperture 72 centrally located with respect to the tubular chamber wall 64 and through which a contact rod 74 is slidably mounted. The contact rod 74 preferably closely slidably fits within the aperture 72 so that there will be substantially no leakage of pressure from the arc chamber 62 at this point. The contact rod 74 obviously may be constructed of any desired conducting material, such, for example, as copper or a copper alloy. The contact rod 74 is provided adjacent its lower end with peripherally spaced, longitudinally extending grooves 76 for a purpose to be herein-after further described.

The upper end of the movable contact rod 74 is provided with a pivot pin 78 extending transversely therethrough with the ends thereof extending beyond the rod 74 to be slidably received in guide slots 80 extending longitudinally of the arc chamber supporting plates 56, to thereby guide the upper end of the movable contact rod 74 for substantially rectilinear movement. An insulating link 82 is pivotally mounted on the pivot pin 78 at one end thereof, and the other end is pivotally connected as by a pivot pin 84 to one end of a crank lever 86. The insulating link 82 may be of any desired insulating material, such, for example, as fiber, a synthetic resin or the like. The crank lever 86 is fixed on an operating shaft 88, the opposite ends of which are journaled in opposite sides of the hollow portion of the cover 32, with one end of the operating shaft 88 extending through the cover wall to have fixedly mounted thereon a manual operating handle 90 having a downwardly extending operating portion 92, adapted to be engaged by manual operating means, such, for example, as a hook stick or the like. The crank lever 86 is normally biased for movement in a counterclockwise direction about the axis of operating shaft 88, by a coil spring 94 coiled about the operating shaft 88,

and having opposite ends thereof 96 and 98, engaged with portions of cover 32 and crank lever 86, respectively. This biasing action of coil spring 94 obviously tends to maintain the movable contact rod 86 in a position adjacent the bottom of the arc chamber 62.

Time delay and lockout mechanism for the circuit breaker contacts are provided for delaying the closing time of the contacts under the influence of coil spring 94, and for maintaining the contacts out of engagement after a predetermined number of quickly succeeding circuit interrupting operations. The time delay means for the contact closing operation utilizes the dashpot cylinder 70 provided integral with the upper end cap 66 of the arc chamber. This cylinder 70 is adapted to receive a piston member 95 having some slight clearance in the cylinder, so as to permit the escape of fluid trapped between the piston 95 and the bottom of the cylinder at a predetermined relatively slow rate. As shown, the lower portion of the piston 95 is hollowed out as at 97 for the reception of a coil compression spring 99, seated at one end on a metal washer 101 on the bottom of the cylinder 70, and the other end of spring 99 bearing against a similar washer 103, provided at the top of the hollow portion 97 in the piston. The spring 99 obviously functions to normally maintain the piston 95 in an extended position with respect to the cylindrical portion 70, normally the position shown in Fig. 1 of the drawing. The piston 95 is preferably of insulating material, such, for example, as fiber or a synthetic resin material.

A pair of ratchet links 100 have one end thereof pivotally mounted at opposite sides of the upper end of piston member 95, as by the pivot pin 102. The other ends of ratchet links 100 are connected by means of a guide pin 104, and one longitudinally extending edge of each ratchet link 100 is provided with a series of notches 106, for cooperation with a pawl to be described. A pawl link 108 is provided with a longitudinally extending slot 110, through which extends the guide pin 104 positioned in holes in the ratchet links 100 for guiding the pawl link 108 for movement with respect to the ratchet links 100. The pawl link 108, as shown, is located between the ratchet links 100, and has secured to opposite edges adjacent the lower end thereof, as shown in Fig. 1, by welding or the like, a stop bar 112 and a pawl bar 114, respectively. The stop and pawl bars 112 and 114, respectively, act to limit pivotal motion of the pawl link 108 about guide pin 104 with respect to ratchet links 100, and longitudinal movement of the pawl link with respect to the ratchet links is limited, of course, by the extent of guide slot 110. The upper end of pawl link 108 is pivotally mounted between a pair of crank arms 116 by a bolt 118 extending therethrough, which bolt is provided with resilient substantially cup-shaped washers 120 at each end thereof to provide a frictional pivotal connection between the crank arms 116 and the pawl link 108. The crank arms 116, as shown, are secured to opposite sides of the crank lever 86, for example, as by welding or the like, so as to move therewith. The flange 36 of cover 32, as shown in Fig. 1, is provided with an integral downwardly extending lip portion 117 which extends downwardly along the inner wall of the insulating casing 2 to support an adjustable stop screw 119 for a purpose to be herein-after described.

In the operation of the mechanism described above, assuming that the movable contact rod 74

is moved upwardly in response to an overload or other fault condition occurring in the circuit, it is obvious that crank lever 86 will be moved in a clockwise direction, thereby stressing coil spring 94, and also causing movement of the crank arms 116 in a clockwise direction. Because of the frictional pivot 118 between the crank arms 116 and the pawl link 108, the stop bar 112 on the link will be maintained in engagement with the smooth edge of ratchet links 100. Dashpot piston 95 will remain substantially in the position shown in Fig. 1, and the pawl link 108 will be withdrawn slightly from between the ratchet links 100. This movement continues until the end of the opening movement of contact rod 74. When the opening means is no longer effective, obviously, coil spring 94 can then operate to move the crank lever 86 in a counterclockwise direction about the axis of shaft 88 to move the contact rod 74 downwardly, and to move the crank levers 116 in a counterclockwise direction. This movement of the crank levers 116 will also move the pawl lever 108 through frictional pivot 118, to bring the pawl bar 114 into engagement with one of the notches 106 in the ratchet levers 100. This position of these levers is illustrated in Fig. 2 of the drawings, wherein the pawl bar 114 is shown as in engagement with the second notch from the lower end of the ratchet links 100. As shown in Fig. 2, the guide pin 104 is in a position below the upper end of the guide slot 110 in the pawl link 108. Continued movement of the crank lever 86 under the influence of coil spring 94 will tend to straighten the toggle formed by crank arms 116 and links 100 and 108 and thereby move the dashpot piston 95 a predetermined distance downwardly into the dashpot cylinder 70. This movement will be relatively slow due to the opposition offered by the dashpot piston and cylinder, and due to the fact that the toggle formed by crank arms 116 and links 100 and 108 is at the beginning of this movement, a considerable distance away from dead-center position. The resistance offered by the dashpot piston and cylinder, of course, is due to the necessity of displacing the oil entrapped in the dashpot cylinder 70 through the small clearance existing between the dashpot piston 95 and the inner wall of the cylinder 70. However, as closing movement of the mechanism proceeds further, the toggle mentioned above approaches its dead-center position, and, consequently, less force need be applied to this toggle because as the lower limit of movement is approached, the dashpot piston 95 is moved a lesser extent for the same amount of rotating movement of operating shaft 88. Inasmuch as the closing force exerted by coil spring 94 is constant, it is obvious that the speed of closing movement is relatively slow at first due to the position of the toggle previously mentioned, but speeds up as it approaches the closed position shown in Fig. 1, because the toggle approaches its dead-center position. This action will enable the circuit breaker contacts to go into final closed position with substantially a snap action, which is obviously desirable, to reduce arcing when the contacts are closed.

It will be noted that as the crank arms 116 and pawl and ratchet links 100 and 108 approach the position shown in Fig. 1, that these links go into and past their dead-center positions, and this latter movement operates to bring the right-hand edge of pawl link 108 as seen in Fig. 1 into engagement with the adjustable stop screw 119, and thereby force the pawl bar 114 out of

the notch 106 in which it had been engaged, and thereby release the dashpot piston 95 to permit it to begin its upward travel to normal position under the influence of spring 99.

When the parts have reached the position shown in Fig. 1, which corresponds to the closed circuit position of the breaker, if the fault on the line has not been cleared, the movable contact rod 74 will substantially immediately be caused to move upwardly again to open the circuit. This will cause the parts to move as before, excepting that when the upper position of the contact rod 74 is reached, or when the limit of clockwise rotation of the crank lever 86 is attained, and the reverse or closing movement begins, pawl bar 114 will engage the third notch from the bottom of the ratchet levers 100. This is because of the length of time required for spring 99 to move dashpot piston 95 upwardly, so that it will not have attained its normal extended position shown in Fig. 1 by the time the breaker starts to reclose on a second substantially immediately succeeding reclosure. With the pawl bar 114 engaged in the third notch in the ratchet levers, the parts will then proceed to reclose as before with the dashpot piston 95 this time being forced a further distance into the dashpot cylinder 70. If the fault still remains on the circuit, the circuit breaker will again open and reclose in the manner described above, except that this time the pawl bar 114 will be engaged in the next succeeding higher notch in the ratchet links 100 and, accordingly, the dashpot piston 95 will be pushed a greater distance into the dashpot cylinder 70. If the fault still has not been cleared, the movable contact rod 74 will again move upwardly to interrupt the circuit, and this time upon attempted reclosure, the pawl bar 114 will engage in the upper notch in the ratchet links 100, and counterclockwise movement of the crank lever 86 will be arrested after a slight movement, due to the dashpot piston 95 striking the bottom of dashpot cylinder 70, and the movable contact rod 74 will thereby be locked or maintained in an open position.

I have described above, a lockout means which operates to maintain the circuit breaker contacts open after three closely successive reclosures of the contacts. This number has been chosen because it has been found that the great majority of faults which are self-clearing will clear in the time necessary for two or three successive reclosures of my breaker. However, it is obvious that any desired number of reclosures may be provided before the breaker locks out, merely by adjusting the dimensions of the dashpot cylinder and piston, and providing an appropriate number of notches in the pawl links 100.

To reset the breaker after the contact rod 74 has been locked out and maintained in an upper position, it is merely necessary to rotate the manual operating handle 90 in a clockwise direction about the axis of shaft 88. A very slight rotation of the crank lever 86 by virtue of the frictional pivot 118, will cause pawl bar 114 to disengage the upper notch 106. It will be noted that this operation is easily accomplished because the only load on the pawl bar 114 is the relatively light spring load 99, and this load will not even be present if the operating rod 90 is moved quickly. With pawl 114 disengaged from the upper notch 106, dashpot piston 95 is free to move upwardly and in a very short time (the time required for the piston to travel the distance between adjacent notches 106), the oper-

ating lever 86 can be released, and the entire mechanism will operate to reclose the movable contact 74 by moving it downwardly to the position shown in Fig. 1 in the manner described above.

Obviously, if the fault clears after the first or second closely succeeding interrupting operation, and the circuit is reclosed, the dashpot piston 85 will be moved upwardly after a predetermined time by the coil spring 89 to its normal position shown in Fig. 1, and the contacts are locked open only after three closely successive interrupting operations, and will never be locked open irrespective of the number of time-spaced interruptions.

Referring to Fig. 1, the contact opening means is mounted on the lower end of arc chamber 62, specifically on the lower end cap 68 of the chamber. The end cap 68 of the chamber is provided with an aperture 128 forming an extension of the passage through insulating tube 84, and which forms between the aperture 128 and the threaded flange of the end cap 68, a shoulder 122 between which and the end of the insulating tube 84, I provided a stop washer 124. The stop washer 124 has an aperture therein substantially smaller than the passage in the arc chamber, and slightly larger than the diameter of the movable contact rod 74. At the outer end of the aperture 128 in end cap 68 of arc chamber 62, I have provided an inwardly extending integral short flange 128, forming a guiding bearing for slidably receiving a contact rod 130 which cooperates with the movable contact rod 74 to control the electric circuit through the interrupter. A substantially U-shaped operating coil yoke 134 of magnetic material, such as soft iron or the like, has one leg thereof secured to end cap 68 of arc chamber 62 as, for example, by machine screws 132 with spacer discs 135 interposed between the end cap 68 and the adjacent leg of yoke 134. The legs of yoke 134 are provided with aligned apertures for receiving a guide tube 136, the passage through which is aligned with the bearing formed by flange 128 for slidably guiding the outer end of contact rod 130. Movement of the contact rod 130 outwardly of the arc chamber 62 is limited by an insulating block 138 secured to the bottom leg of yoke 134 by machine screws 140, to cover the lower end of guide tube 136. As shown, the lower end of contact rod 130 is hollowed out to receive a coil compression spring 142, one end of which engages the insulating block 138, and the other end of which engages a metallic disc 146 in the bottom of the hollow portion 144, to normally urge the contact rod 130 upwardly into engagement with the stop washer 124. Confined between the legs of the U-shaped yoke 134, and wound about guide tube 136, is a coil 148, one end 154 of which is connected to a terminal screw 150, threaded into the outer lower surface of the insulating block 138. The screw 150 also functions to secure to the block in conducting relation to the conductor 154, a curved substantially U-shaped resilient contact strip 152, which, as shown, is adapted to engage the enlarged head 20 of bolt 18 of the lower terminal assembly 6 of interrupter casing 2.

The other end of coil 148 is electrically connected by a conductor 155 to the lower end cap 68 of the arc chamber. Movable contact rod 74 is electrically connected by conductor 156 to the interrupter casing cover 32, as by having the ends of the conductor soldered or otherwise connected to these parts, respectively.

Referring to Fig. 6 of the drawing, it will be apparent that cover 32 for interrupter casing 2 is provided with an angle piece 158, one leg of which is secured to flange 38 of the cover as by screws 160, and the other leg of which has secured thereto, as by welding or the like, a conductor terminal socket 162, having a clamping screw 164 threadedly engaged through the outer wall thereof to clamp a conductor in the socket 162.

10 The electrical circuit through the interrupter shown in Figs. 1 to 4, inclusive, may now be traced from the terminal socket 162 on cover 32, through the cover, conductor 156, to movable contact 74, contact rod 130, lower end cap 68, conductor 156, solenoid coil 148, conductor 154, resilient contact strip 152, bolt 18 of the lower contact assembly 6, and terminal strap 28 to another line conductor.

Upon the occurrence of an overload in the circuit in which my interrupter is connected, obviously if the overload is greater than a predetermined value, it will cause solenoid coil 148 to draw the contact rod 130 downwardly to substantially the dotted line position shown in Fig. 1. It will be noted that the upper end of contact rod 130 has a full central circular portion 166 spaced from the upper end thereof, and above and below this central portion 166 are provided spaced longitudinally extending grooves for the purpose of venting the arc chamber. The contact rod 130, or at least a lower portion thereof, is of a conducting magnetic material, such, for example, as iron or an alloy thereof. When the conductor rod 130 is attracted to the dotted line position by the solenoid coil 148, the full central section 166 of the contact rod will be positioned opposite the flange 128 on the lower terminal cap so as to close off the lower end of the arc chamber 62. Movable contact rod 74 may, due to any play which may exist in the pivotal connections with link 82 and crank lever 86, follow the contact rod 130 downwardly a short distance, but cannot move a distance corresponding to the entire travel of contact rod 130 due to engagement of pawl link 168 with the adjustable stop 118. The contact rod 130 thereby moves further than contact rod 74, downwardly, under the influence of solenoid coil 148, so that a gap is created between the contact rods 74 and 130, and an arc is struck therebetween. Preferably the insulating casing 2 is filled with an arc-extinguishing liquid, such as oil, up to a level indicated by the dash line L, and consequently the arc chamber 62 is completely filled with such liquid. The arc formed will generate gases due mainly to decomposition of the arc-extinguishing fluid, and inasmuch as the arc chamber is substantially closed, the pressure generated therein by such gases will operate to move the contact rod 74 upwardly in a piston-like manner, out of the arc chamber, and move the mechanism associated therewith against the bias of coil spring 84 to produce a large gap between the contact rods 74 and 130. If the overload is of a large magnitude, solenoid coil 148 and the gas pressure built up in arc chamber 62 may have sufficient force to move the contact rod 130 against the bias of spring 142 downwardly below the dotted line position shown in Fig. 1 to the limit of its travel in a downward direction against insulating block 138. This will move the full circular section 166 of the upper end of contact rod 130 below the flange 128 on end cap 68, so as to bring the slots 168 in the upper end of the contact rod 130 adjacent the flange 128 so that venting of the arc gases may take place through the passages thus

created and through the space between the upper leg of yoke 134 and end cap 68. The lower contact 130 thereby functions as an overpressure relief means to prevent damage to the arc chamber in interrupting high current arcs. When the circuit has been interrupted and the arc gases dissipated by the venting means described above and by a vent created by the moving contact 74 at its upper limit of travel by presentation of grooves 76 in the lower end of this contact rod adjacent the aperture 72 in the upper arc chamber end cap 66, spring 142 will move the contact rod 130 upwardly against the stop washer 124 to the position shown in Fig. 1. It is seen that in this position of the contact rod 130 new vent passages similar to the passages described above are created, by the grooved portions 168 of the rod below the full circular section 166 thereof, being presented adjacent to the flange 128 on the lower end cap 68. Inasmuch as at this time the upper contact rod also is in a venting position with respect to the upper end of the arc chamber 62, the arc gases will be permitted to escape from the arcing chamber, and under the influence of the head of arc-extinguishing liquid, liquid may flow in the bottom venting passages to replace the arc gases escaping from the top of the arc chamber, thereby providing for flushing out of the arc chamber after each interrupting operation and replacement of the used arc-extinguishing liquid with new liquid from the reservoir maintained in insulating casing 2.

Following this venting and flushing out of the arc chamber 62, the circuit breaker contact rod 74 is moved downwardly and into engagement with the contact rod 130 by coil spring 94 with the time delay and final snap action, all as previously described. If the fault is cleared when the circuit breaker contacts reclose, the dashpot piston 95 resets as previously described. On the other hand, if the fault still exists, solenoid coil 148 will operate to again open the contacts, and contact rod 74 will be forced upwardly as for the first opening described above. The operating mechanism will then operate to reclose the contacts a predetermined number of times if the fault continues, until the contact rod 74 is locked in an upper open position by the lockout means, all as previously described.

Instead of providing for movement of the lower contact by a solenoid coil 148, as described above, I may provide current-responsive means for moving the upper contact rod 74 slightly upwardly to establish an arc, and then rely upon pressure in the arc chamber to continue movement of this rod to its fully open position. With such a structure, obviously the lower contact may be fixed with respect to the arcing chamber 62. Such a construction is the joint invention of H. L. Rawlins and myself, and is disclosed and claimed in our joint application Serial No. 346,300, filed July 19, 1940, now Patent No. 2,318,421, issued May 4, 1943, to the same assignee of this application.

Referring to Figs. 5 and 6 of the drawings, I have shown such a construction embodied in a circuit breaker of the automatic reclosing and lockout type previously disclosed, and, accordingly, like parts are provided with like reference numerals. As described in the above mentioned co-pending application, a trip lever 170 is provided for initially moving the contact rod 74 upwardly a short distance to establish an arc within the arc chamber 62. This trip lever 170 is substantially hook-shaped in form and is pivotally

mounted adjacent the point of the hook on a pivot pin 172, mounted between the supporting plates 58 for the arc chamber 62. A coil spring 174 is provided about the pivot pin 172, and has one end thereof 178 engaging with the upper end cap 66 of the arc chamber, and the other end thereof 176 is engaged with a part of the trip lever 170 extending beyond the pivot 172, to continuously bias the trip lever 170 for rotation about its pivot pin 172 in a counterclockwise direction. As shown, the pivot pin 178 joining the upper end of contact rod 74 and insulating link 82 is received substantially in the bight portion of the trip lever 170, so that it is engaged by the lever when the lever is moved by spring 174 from the position shown in Fig. 5, to thereby move the contact rod 74 upwardly a slight distance against the bias of spring 94. The upper end of the trip lever 170 is provided with a projecting catch portion 180 secured between insulating plates to the upper end of the trip lever, for example, as by rivets 179. The construction of the trip lever and its operation is more fully described, and claimed, in the co-pending application mentioned above.

One leg of a U-shaped iron yoke 181 is secured to the top wall of the interrupter cover 32, as by machine screws 183, as shown. A solenoid coil 182 is mounted between the legs of the yoke 181 for cooperation with a plunger 184 of magnetic material, such, for example, as iron or the like, slidably mounted in the coil and provided with a hollow upper end portion 186, for reception of a coil compression spring 188, the other end of which is received in a stationary sleeve 190 secured to the upper leg of yoke 181, and which also acts to guide the upper end of plunger 184 which is telescopically mounted with respect to guide sleeve 190. The outer end of solenoid plunger 184 is reduced in cross section to provide a stop shoulder 192 for engagement with the lower leg of yoke 181 adjacent aperture 194 therein, and through which extends the reduced lower end of the solenoid plunger. Obviously, coil spring 188 functions to maintain the plunger 184 in its outer position shown in Figs. 5 and 6. Below the yoke 181 the plunger is further reduced in section to form a latch portion 196, which in the normal extended position of the plunger extends into the path of movement of trip lever 170 under the influence of spring 174.

A bimetal strip 200 has one end thereof secured to flange 38 of cover 32, as by screws 198, and the other end thereof is provided with a transversely extending adjustable latch portion 202, which is adjustable by virtue of being threadedly engaged in an aperture through the free end of the bimetal strip 200. The bimetal strip 200 is constructed in a manner well known in the art, of at least two laminations intimately secured together as by welding or the like, which laminations are of materials having different coefficients of expansion. Thus, as shown, the upper lamination of bimetal strip 200 should be of a material having a relatively low coefficient of expansion, such as steel or the like, and the lower lamination should be of a material having a relatively higher coefficient of expansion, such as brass or the like, so that when the strip becomes heated, the outer end thereof will deflect upwardly to bring the latch portion 202 above the path of movement of catch portion 180 on trip lever 170. It will be noted that the latch portions 196 and 202 on the solenoid plunger and bimetal strip, respectively, are relatively offset from each other along the path of movement of

catch 180 on trip lever 170 when moved in a counterclockwise direction by coil spring 174. The reason for this will become apparent in the description of the operation of this trip mechanism given below.

The electrical circuit through the circuit breaker shown in Figs. 5 and 6 proceeds from terminal socket 162 on cover 32 through cover 32, bimetal strip 200, conductor 204, solenoid coil 182, conductor 206 to contact rod 74, and thence to the lower fixed contact of the breaker and the lower breaker terminal in a manner fully described in the previously mentioned copending application. It can be seen then, that the bimetal strip 200 and solenoid coil 182 are connected in series in the circuit through the circuit breaker shown in Figs. 5 and 6.

The time delay and lockout means shown in Figs. 5 and 6 and operating mechanism for reclosing the circuit breaker and resetting the same after lockout is identical with that previously described, and hence will not be again described in detail here to avoid repetition.

Upon the occurrence of an overload in the embodiment of my invention shown in Figs. 5 and 6, solenoid coil 182 is instantly energized and draws plunger 184 upwardly against spring 188, thereby lifting the plunger latch 198 away from catch 180 on trip lever 170. The trip lever will then rotate counterclockwise under the influence of its spring 174, about pivot 172, until catch 180 strikes latch 202 on the bimetal strip 200. This travel obviously will be very short, and, of course, will not be sufficient to move the contact rod 74 upwardly out of engagement with the fixed contact of the breaker, and the breaker will not be tripped. The overload current also passing through the bimetal strip 200 causes it to gradually heat up, and after a predetermined time, it will deflect upwardly until its latch projection 202 releases the catch 180 on trip lever 170, to permit the trip lever to rotate to the extreme limit of its travel, thereby raising the contact rod 74 sufficiently to establish an arc in the arc chamber 62, and the pressure of the arc gases will then operate in the manner previously described to move the contact rod 74 upwardly to its limit of travel, and thereby interrupt the circuit. As fully explained in my previously mentioned joint copending application, travel of contact rod 74 upwardly by the pressures developed in arc chamber 62 causes pivot pin 78 to engage the adjacent edge of trip lever 170 to rotate the same back to the position shown in Fig. 5, and thereby enable it to reset on latch projection 196 of the solenoid plunger which will be projected outwardly by spring 188 as soon as the circuit is interrupted within arc chamber 62. This will occur substantially instantaneously after tripping, but at this time the bimetal strip 200 will not have cooled sufficiently to allow its latch projection 202 to move back downwardly into the path of movement of the catch 180. The solenoid plunger 184, however, will reset to the position shown in Fig. 5 substantially as quickly as the breaker contact rod pivot pin 78 can reset trip lever 170. This resetting action will move the trip lever catch 180 to the right of solenoid latch 198, as seen in Fig. 5, and the trip lever will be latched in this position, although the bimetal is not in a latching position. After the breaker contact 74 has moved to the upper limit of its travel and the circuit has been interrupted within the arc chamber 62, it is moved downwardly to then reclose the circuit

through the breaker, by coil spring 94, with a time delay caused by the dashpot in the same manner as described in connection with the embodiment of my invention shown in Figs. 1 to 4. As the breaker closes in on a short circuit or an overload which has not cleared, it will be tripped out substantially immediately by solenoid coil 182. The bimetal latch 202 will not prevent this tripping because it is still in a tripped or heated position. This will also be true for the second or third tripping, if the breaker does not close back in on a normal circuit after the second or third reclosure. If, however, the circuit is cleared after the second or third reclosure, the bimetal strip 200 will gradually cool and resume the position shown in Fig. 5, so that at some later time when an overload comes upon the circuit, it will then trip the circuit breaker with thermal time lag characteristics as it did the first time.

It can be readily seen from the foregoing that I have provided a device for tripping an automatic reclosing circuit breaker, which has thermal time lag characteristics upon the first operation thereof, and magnetic or instantaneous characteristics upon each succeeding operation unless a considerable time elapses between such operations. The particular structure described above and illustrated in Figs. 5 and 6 is specifically disclosed and claimed in my copending application Serial No. 582,829, on Circuit Interrupters, filed March 15, 1945, as a division of this application, and assigned to the same assignee of this application.

It will be apparent from the foregoing that I have provided a novel type of automatic reclosing circuit breaker which is adapted to automatically reclose a circuit following an interrupting operation a predetermined number of times, and then lock the circuit breaker contacts in an open circuit position. According to my invention, the pressure caused by the arc gases is confined in an arc chamber to open the circuit breaker contacts, and I have disclosed specifically two different species of tripping means for initially separating the contacts sufficiently to establish an arc in such an arc chamber. My invention also embodies novel time delay means operable on reclosure of the breaker contacts, and operable in response to a predetermined number of successive reclosures to lock the circuit breaker contacts in an open circuit position. By employing a fluid time delay means for delaying closing of the breaker contacts, which uses the circuit breaker arc extinguishing fluid, I am enabled to insure complete flushing of arc chamber 62 irrespective of the viscosity of the fluid. This is important where a fluid such as oil is used which is subject to changes in viscosity in response to temperature changes which are met in actual service conditions.

It is also apparent that all of the operating parts of my novel breaker are mounted on the container cover 32. This permits ready inspection of the same by merely removing the cover, and obviates the necessity of securing any parts to the porcelain container 2.

Although the trip mechanisms disclosed, the arcing chamber, and contact operating mechanisms are all disclosed in a single unitary structure wherein they have particular features of novelty and cooperation, it will be obvious that these and other features of my invention may also be used separately or in connection with other circuit breaker constructions.

Having described preferred embodiments of my

invention in accordance with the patent statutes, I desire that it be understood that my invention is to be interpreted as broadly as possible and not limited to the specific embodiments disclosed, inasmuch as it will be obvious, particularly to persons skilled in the art, that many changes and modifications may be made in these particular structures without departing from the broad spirit and scope of my invention. Therefore, I desire that my invention be not limited in any respect except as defined in the following claims, and as required by the prior art.

I claim as my invention:

1. In a circuit interrupter including a substantially closed arc chamber, separable contacts in said chamber at least one of which is slidably mounted in a wall of said chamber, and means for moving the other of said contacts away from said one contact to draw an arc therebetween, whereby the pressure developed by said arc operates to increase said separation by forcing said one contact to slide outwardly with respect to said chamber.

2. In a circuit interrupter including a substantially closed arc chamber, separable contacts in said chamber, at least one of which is slidably mounted in a wall of said chamber, means for moving the other of said contacts away from said one contact to draw an arc therebetween, whereby the pressure developed by said arc operates to increase said separation by forcing said one contact to slide outwardly with respect to said chamber, and a vent for said chamber controlled by said other contact to close said vent when said other contact is moved to draw an arc, and to open said vent when said contacts are in engagement.

3. In a circuit interrupter including a substantially closed arc chamber, separable contacts in said chamber, at least one of which is slidably mounted in a wall of said chamber, means for moving the other of said contacts away from said one contact to draw an arc therebetween, whereby the pressure developed by said arc operates to increase said separation by forcing said one contact to slide outwardly with respect to said chamber, a vent for said chamber controlled by said other contact to close said vent when said other contact is moved to draw an arc, and to open said vent when said contacts are in engagement, and means controlled by said one contact to vent said chamber when at its outer limit of travel with respect to said chamber, at a point spaced from said first mentioned vent, to provide for flushing of said arc chamber.

4. In a circuit interrupter including a substantially closed arc chamber, separable contacts in said chamber, at least one of which is slidably mounted in a wall of said chamber, means for moving the other of said contacts away from said one contact to draw an arc therebetween, whereby the pressure developed by said arc operates to increase said separation by forcing said one contact to slide outwardly with respect to said chamber, a vent for said chamber controlled by said other contact to close said vent when said other contact is moved to draw an arc, and to open said vent when said contacts are in engagement, and said other contact being movable beyond its arc drawing position to open said vent, and resilient means opposing said movement, whereby said other contact also operates as a pressure relief means for said arc chamber.

5. In a circuit breaker, a container for an arc extinguishing fluid, a chamber adapted to be

closed at least during a circuit interrupting operation and at least partially submerged in said fluid, separable contacts in said chamber, at least one of which is slidably mounted in a wall of said chamber, means for separating said contacts to draw an arc therebetween, whereby the pressure developed by said arc operates to increase said separation by forcing said one contact to slide outwardly with respect to said chamber, means controlled by said contacts in response to a circuit interrupting operation thereof to vent said chamber at a plurality of spaced points, at least one of which is below the level of said fluid and another of which is at a different level, whereby said chamber is flushed out and supplied with a fresh quantity of said fluid after each circuit interrupting operation.

6. In an automatic reclosing circuit interrupter, separable contacts, at least one of which is movable to open and close said contacts, dashpot means having a pawl and ratchet connection to said movable contact such that a part of said means is advanced a predetermined amount in response to a movement of said contact in one direction, biasing means for slowly restoring said part to its normal position, and stop means positioned to be engaged by said part to prevent closure of said contacts in response to advancement of said part an amount greater than said predetermined amount by a predetermined number of successive circuits interrupting operations.

7. In a reclosing circuit interrupter, separable contacts, at least one of which is movable to open and close said contacts, pivoted control lever means connected to said one contact, time delay means having a movable part connected to said lever means by pivoted links which are mutually connected for limited sliding and pivotal movement, and include, respectively, pawl and ratchet elements, one of said link pivots being a frictional pivot, means positioned to engage one of said links in its position corresponding to the closed position of said contacts for releasing said pawl and ratchet elements, and said frictional pivot causing engagement of said pawl and ratchet elements upon closing movement of said one contact.

8. In a circuit interrupter, a fluid container having an open end, a terminal cap for said end, an interrupting assembly mounted on said cap and including spaced supporting members depending from said cap for supporting an arc chamber at a point spaced from said cap, separable contacts in said chamber one of which is electrically connected to said cap, at least one of said contacts being movable through a wall of said chamber, and guide means on at least one of said supporting members intermediate said cap and chamber and engaging said movable contact for guiding its circuit opening and closing movements.

9. In an automatic reclosing circuit interrupter, separable contacts, at least one of which is movable to open and close said contacts, fluid pressure time delay means having a connection to said movable contact such that said means is actuated away from a normal position by said movable contact only by movement thereof in a direction to close said contacts, said time delay means being biased to its normal position, and stop means positioned to be engaged by a part movable with said time delay means to prevent closure of said contacts in response to a predetermined number of successive openings thereof, said connection of said time delay means to said movable contact including toggle means ar-

ranged to attain substantially its dead center position at the closed position of said contacts, whereby less force is required to close said contacts as they approach their fully closed position.

10. In an automatic reclosing circuit interrupter, separable contacts, at least one of which is movable to open and close said contacts, fluid pressure time delay means having a connection to said movable contact such that said means is actuated away from a normal position by said movable contact only by movement thereof in a direction to close said contacts, said time delay means being biased to its normal position, means positioned to be engaged by a part movable with said time delay means to prevent closure of said contacts in response to a predetermined number of successive openings thereof, said connection of said time delay means to said movable contact including toggle means arranged to attain substantially its dead center position at the closed position of said contacts, whereby less force is required to close said contacts as they approach their fully closed position, said contacts being biased closed, and current responsive means for effecting opening of said contacts.

11. In a reclosing circuit interrupter, separable contacts, at least one of which is movable to open and close said contacts, fluid pressure time delay means having a connection to said movable contact such that said means is actuated by said movable contact away from a normal position only by movement thereof in a direction to close said contacts, said time delay means being biased to its normal position, means positioned to be engaged by a part movable with said time delay means to prevent closure of said contacts in response to a predetermined number of successive openings thereof, said connection of said time delay means to said movable contact including toggle means arranged to attain substantially its dead center position at the closed position of said contacts, whereby less force is required to close said contacts as they approach their fully closed position, said contacts being biased closed, and current responsive means for effecting opening of said contacts, and said contact closing resilient means also connected to said movable contact by toggle means arranged to approach dead center position in closing said contacts.

12. In a circuit breaker, a container for an arc extinguishing fluid, a substantially closed arc chamber at least partially submerged in said fluid and substantially filled with said fluid, separable contacts in said chamber at least one of which is slidably mounted in a wall of said chamber, means responsive to an interrupting operation of said breaker for flushing said chamber with said fluid, fluid time delay means at least partially submerged in said container so as to utilize said fluid, and said time delay means associated with said one contact to delay the closing movement thereof.

13. In a circuit breaker, a container for an arc extinguishing fluid, a substantially closed arc chamber adapted to be at least partially submerged in said fluid, separable contacts in said chamber, at least one of which is slidably mounted in a wall of said chamber, electro-responsive means for moving the other of said contacts away from said one contact to draw an arc therebetween, whereby the pressure developed by said arc operates to increase said separation by forcing said one contact to slide outwardly with respect to said chamber, and means responsive to a predetermined number of successive circuit

interrupting operations of said contacts for maintaining said contacts disengaged.

14. In an automatic reclosing circuit interrupter, a fluid container adapted to be substantially filled with an arc extinguishing liquid, separable contacts at least one of which is movable to open and close said contacts, said contacts positioned in said container below the liquid level thereof to utilize said liquid to extinguish the arc, fluid pressure time delay means having a connection to said movable contact such that said means is actuated by said movable contact at least by movement thereof in a direction to close said contacts, and said time delay means also positioned in said container below the liquid level to utilize said fluid in the operation thereof and operating independently of the complete extent of opening movement of said contacts.

15. In an automatic reclosing circuit interrupter, separable contacts at least one of which is movable into and out of engagement with the other, electro-responsive means for separating said contacts to interrupt the circuit, said movable contact being biased towards the other of said contacts to automatically close the circuit after a circuit interrupting operation, time delay means having a connection with said movable contact for at least delaying movement of said one contact into engagement with the other of said contacts, and said connection of said time delay means and movable contact comprising mechanical motion transmitting means the mechanical advantage of which varies during its movement for gradually reducing the delaying effect of said time delay means in response to movement of said one contact toward the other of said contacts, whereby to provide for gradual acceleration of the movement of said one contact in a circuit closing operation.

16. In a reclosing circuit interrupter, separable contacts, at least one of which is movable to open and close said contacts, time delay means having a connection to said movable contact such that said means is actuated by said movable contact at least by movement thereof in a direction to close said contacts, said connection of said time delay means to said movable contact including toggle means arranged to attain substantially its dead center position at the closed position of said contacts, whereby less force is required to close said contacts as they approach their fully closed position.

17. In an automatic reclosing circuit interrupter, separable contacts, at least one of which is movable to open and close said contacts, time delay means having a connection to said movable contact such that said means is actuated by said movable contact at least by movement thereof in a direction to close said contacts, said connection of said time delay means to said movable contact including toggle means arranged to attain substantially its dead center position at the closed position of said contacts, whereby less force is required to close said contacts as they approach their fully closed position, resilient means biasing said contacts closed, current responsive means for effecting opening of said contacts, and said contact closing resilient means also connected to said movable contact by toggle means arranged to approach dead center position in closing said contacts.

18. In a circuit breaker, a container for an arc extinguishing fluid, a chamber adapted to be closed at least during a circuit interrupting operation and at least partially submerged in said

fluid, separable contacts in said chamber arranged to be forced apart by fluid pressure in said chamber, means for separating said contacts to draw an arc therebetween, whereby the pressure developed by said arc operates to increase said separation, means responsive to a circuit interrupting operation to vent said chamber at a plurality of spaced points, at least one of which is below the level of said fluid and another of which is at a different level, whereby said chamber is flushed out and supplied with a fresh quantity of said fluid after each circuit interrupting operation.

19. In a circuit breaker, a container for an arc extinguishing fluid, a substantially closed arc chamber at least partially submerged in said fluid and substantially filled with said fluid, separable contacts in said chamber, electro-responsive means for separating said contacts, said contacts being biased into engagement to automatically close the circuit in response to a circuit interrupting operation, means responsive to an interrupting operation of said breaker for flushing said chamber with said fluid, fluid time delay means at least partially submerged in said container so as to utilize said fluid, and said time delay means associated with one of said contacts to delay the closing movement thereof.

20. In an automatic reclosing circuit breaker, a container for an arc extinguishing liquid, separable contacts positioned in said container so as to be submerged in said liquid for extinguishing the arc formed when said contacts separate, electro-responsive means for causing separation of said contacts to interrupt the circuit, said contacts being biased closed in response to a circuit interrupting operation to automatically reclose the circuit, and fluid time delay means positioned in said container below the liquid level so as to utilize said arc extinguishing liquid for delaying closing movement of said contacts and operating independently of the complete extent of opening movement of said contacts.

21. In a circuit breaker, a container for an arc extinguishing fluid, a chamber adapted to be closed at least during a circuit interrupting operation and at least partially submerged in said fluid, separable contacts in said chamber arranged to be forced apart by fluid pressure in said chamber, means for separating said contacts

to draw an arc therebetween, whereby the pressure developed by said arc operates to increase said separation, means biasing said contacts into engagement, fluid time delay means in said container and utilizing said fluid to delay movement of said contacts into engagement, means responsive to a circuit interrupting operation to vent said chamber at a plurality of spaced points, at least one of which is below the level of said fluid and another of which is at a different level, whereby said chamber is flushed out and supplied with a fresh quantity of said fluid after each circuit interrupting operation, irrespective of the viscosity of said fluid.
